UNITED STATES PATENT OFFICE

RALPH S. WILLIAMS, OF GOLETA, CALIFORNIA

FASTENER

Application filed December 22, 1930. Serial No. 503,879.

This invention relates to fasteners of the type employed, for example, for latching gates and doors in open or closed position. This fastener is of the type in which a ring constitutes the latch bolt or member, and an object of this invention is to insure against release of the fastener by cattle or other animals that may have access to the fastener.

Another important object is simplicity of construction combined with strength.

Other objects and advantages will appear in the subjoined detailed description.

The accompanying drawings illustrate the invention.

15 Figure 1 is a side elevation of a fastener constructed in accordance with the provisions of this invention, the case being shown in section and one of the rings being shown retracted by a locking bar, which is indicated 20 in dotted lines.

Figure 2 is a view similar to Figure 1, excepting that both rings are shown in their latching positions and the locking bar between said rings. Broken lines indicate 25 other positions of one of the rings and its actuating lever.

Figure 3 is a vertical section on the irregular line indicated by 3—3, Figure 2.

Figure 4 is a view similar to Figure 1, 30 showing a modified form of the invention.

First describing the form of the invention illustrated in Figures 1 to 3, there is provided a relatively thin case 6 which may be made of sheet metal or other suitable material.

35 The case 6, in this instance, comprises side walls 7, end walls 8, and a cover member 9. The cover member 9 is provided centrally thereof with an opening 10. The bottom of the case is open as indicated at 11 and the opening 11 extends the length and breadth of the case.

Any suitable means may be provided for securing the case to its support and, in this instance, bolt holes are shown at 12 in the 45 sides of the case for the reception of bolts, not shown. A tubular spacer 71 is provided for the center bolt to prevent the side walls of the case from collapsing when said bolt is tightened. Though it is preferable to secure the case to a stationary member as, for

example, one of the gate posts, it is immaterial whether the case be placed on the post or on the gate. Assuming that the case is mounted on the gate post, the gate will then be provided with a locking bar 13 of any suitable construction, said bar being mounted on the gate so as to project from the vertical free edge of said gate.

Tiltably mounted within the case 6 is an operating lever 14 provided near its opposite ends with pins 15 from which are adapted to hang rings 16 that constitute the latch bolts of the fasteners. In this instance, the rings 16 lie in a common plane and they are interposed between one of the side walls 7 and a flat plate 17 of the lever 14. The plate 17 is connected at its top by a horizontal web 18 to a handle 19 that projects upwardly through the opening 10. The lever 14 thus comprises the handle 19, the web 18 and the plate 17.

Since the handle 19 projects upwardly, it is not readily accessible to horses and cattle that may be confined within an enclosure to which the gate or door may give access, and thus operation of the lever 14 by horses and cattle is practically impossible.

The pins 15 are fixed and project through the holes 20 in the plate 17 and said pins are longer than the thickness of the plate 17 of the lever 14 so that the ends of the pins 15 project beyond the opposite faces of the plate 17 into guide slots 21 formed in the case walls 7. The slots 21 may be arcuate, as shown, in order that when the lever is rocked one of the pins 15 will move in an arcuate path around the axis of the other pin 15. The lever 14 will rock in opposite directions so as to raise either of the pins 15.

The combined thickness of one of the rings 16 and of the plate 17 is but slightly less than the distance between the case walls 7 so that said case walls function to guide the lever and rings.

The radius of each of the rings is slightly 45 less than the distance from the axis of the associated pin 15 to the adjacent inner face of the case wall 8 when said pin 15 is at the lower end of the slot 21 in which it moves so that any pressure coming against either ring,

tending to push said ring outwardly, will thus cause said ring to engage the adjacent end wall 8 of the case, which end wall thus functions as an abutment to limit outward movement of the ring, while the pin limits downward movement of said ring.

It is to be noted that the rings are suspended from the pins 15 so that when said pins are at the lower ends of the slots 21 approximately two-thirds of each ring will project below the bottom of the case. This is important as considerable sagging of the gate on its hinges may occur without causing the locking bar 13 to drop to a level that would necessitate lowering of the case on the gate post for proper latching.

The construction and operation of the invention will be readily understood from the foregoing and, briefly stated, the operation 20 is as follows: Assuming that the rings 16 are in their lowered positions, as in solid lines in Figure 2, and that the gate is open, swinging shut of the gate will cause the locking bar 13 to engage and retract one of the rings 25 16 as shown in solid lines in the right hand portion of Figure 1 where the elevated ring is shown in a position that it occupies before being fully retracted. As the locking bar moves toward the left in Figure 1, the right 30 hand ring is raised still further by the locking bar so as to permit the locking bar to pass into the space below the middle portion of the case. As soon as the locking bar 13 passes by the right hand ring said ring drops 35 and thus the locking bar is held against lateral motion in opposite directions by the rings. It will be readily seen that the locking bar may swing into latching position from either direction.

40 To release the locking bar so that the gate may be swung open, the handle 19 will be urged to the right or left in Figure 2 so as to retract either the left hand ring or the right hand ring. Assuming that it is desired to 45 open the gate to the right in Figure 2, the handle 19 will be moved to the left until the lever and the right hand ring are in the positions shown in broken lines in Figure 2. It will be seen that the right hand ring is 50 then retracted wholly within the case so that the locking bar 13 can move laterally to the right without striking the retracted ring.

55 It will be noted that the slots 21 permit of retractive movement of the rings, when the locking bar engages said rings, without such movement being imparted to the lever 14 which, accordingly, remains stationary, as clearly shown in Figure 1.

60 Now describing the modified form of the invention illustrated in Figure 4, the elements that functionally correspond with those hereinbefore described are indicated by the same reference characters with the addition of the suffix "a". The main difference

in construction of this form over the previously described form is that there is but one ring 16^a and pin 15^a and, whereas the lever 14 has a movable fulcrum 15, the fulcrum pin 23 of the lever 14^a is stationary, the ends of the 70 pin 23 projecting into the case side walls 7^a. The operation of this form of the invention will be readily understood from the description above of the first described form of the invention. 75

I claim:

1. A fastener comprising a case provided with openings in its top and bottom and with slots in its side walls, a lever provided with transversely extending pins near its opposite 80 ends and projecting into the slots, said pins acting alternately as fulcrums for the lever when the lever is rocked in opposite directions, the lever provided with a handle projecting upwardly through the top opening, 85 and rings loosely hung on the pins, the end walls of the case limiting movement of the rings away from each other.

2. A fastener comprising a case provided with openings in its top and bottom and with 90 slots in its side walls, a lever provided with a plate and with pins projecting through the plate near the ends of said plate and projecting into the slots in the side walls, the pins 95 acting alternately as fulcrums for the lever when the lever is rocked in opposite directions, the lever provided with a handle projecting upwardly through the top opening, and rings loosely hung on the pins, the end 100 walls of the case limiting movement of the rings away from each other.

Signed at Santa Barbara, California, this 12th day of December, 1930.

RALPH S. WILLIAMS.
